STEAM TRAP

Leo P. Flood, Sunnyside, N. Y.

Application June 9, 1930, Serial No. 459,874

3 Claims. (Cl. 137—103)

The invention relates to traps such as are used for venting water from steam mains and the like.

In a steam trap it is desirable that the trap outlet valve be opened and closed quickly and positively to prevent so-called "wire drawing" with its resultant destructive effects on the valve.

According to a preferred embodiment of the invention, the steam trap may comprise a casing having a removable head, the head being provided with a removable cap. A bucket float may be provided in the casing, and the head may be provided with an auxiliary chamber having a depending tube communicating with the interior of the bucket float. The discharge valve may be disposed in the auxiliary chamber, and the seat of the valve may be located in the cap and may be removable. A spindle may be connected to the bucket float, passing through the depending tube, to operate the valve closing it when the bucket float rises, and opening it when the bucket float drops.

A lever arrangement may connect the spindle and valve disc multiplying the force exerted on the valve disc and a lost motion connection may be provided between the lever and the disc so that the float may gain considerable momentum, causing the lever to strike a blow on the valve disc to open the valve.

If desired, the valve seat may be replaced with valve seats having orifices of different sizes, and provision may be made so that the adjustment or position of the operating parts is not required to be changed, the valve disc also seating in the same position irrespective of the particular size of seat.

In this way substantially the same net force will open the valve no matter what steam pressure is used.

The invention also consists in certain new and original features of construction and combinations of parts hereinafter set forth and claimed.

Although the novel features which are believed to be characteristic of this invention will be pointed out with particularity in the claims appended hereto, the invention itself, as to its objects and advantages, the mode of its operation and the manner of its organization may be better understood by referring to the following description taken in connection with the accompanying drawings forming a part thereof, in which

Figure 1 is a top plan view of the trap;

Figure 2 is a section on the line 2—2 of Figure 1;

Figures 3 and 4 are sections taken on the lines 3—3 and 4—4 respectively of Figure 2; and

Figures 5 and 5a are details illustrating the operation of the valve disc with different size valve seats.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, a practical commercial embodiment of the invention is disclosed, but as such illustration is primarily for purposes of disclosure, it will be understood that the structure may be modified in various respects without departure from the broad spirit and scope of the invention as hereinafter defined and claimed.

Referring now to the drawings, the trap comprises a body or casing 10, having a removable cover 11, the casing and cover being provided with meeting surfaces between which a gasket 12 is disposed. Suitable bolt members 100 may be provided for fastening the cover and casing together.

The casing is provided with a threaded inlet opening 13, divided into two branch openings 14. The casing is also provided with a threaded outlet opening 15. It will be understood that the inlet opening 13 will be connected to the steam pipe, or other device, it is desired to drain and that the outlet opening 15 will be connected to a pipe delivering the drained water to any desired location. A plug 16 may be threaded into the bottom of the casing for draining and cleaning purposes.

Located in the casing 10 is an open top bucket float 17 connected to a spindle 18, which has a reduced threaded portion 19 passing through the bottom of the float, and having threaded thereon an enlarged nut 20 acting also as a weight to properly weight the bucket assembly. The spindle may be provided with a plurality of spacing members 21, which have guiding relation with a tube 22 threaded into the wall 23 of the auxiliary chamber 101. The spindle 18 passes through the tube 22 into the auxiliary chamber 101 for operating the valve, as will be hereinafter explained more in detail.

Located on the top of the cover 11 is a removable cap 24 suitably bolted to the cover by bolts 102, there being a gasket 32 between the cap 24 and the cover 11 to make a water-tight joint, as will be understood by those skilled in the art. The cap 24 is provided with a removable plug 28 for giving access to the valve seat.

The cap 24 is provided with a depending annular flanged shoulder 25, which seats a flanged valve seat 26. An annular nut member 27 having a suitable screw driver slot is threaded into the 5 shouldered flange 25 to securely hold the valve seat 26 in position. The cap 24 is provided with an opening 30 communicating with the valve seat 26, and the cover 11 is provided with an opening 31 communicating with the opening 30 and the 10 outlet opening 15 to convey the water discharged through the valve seat 26.

Referring now to Figure 5, the valve seat 26 is provided with an orifice 38 and a tapered mouth 37 against which seats the valve plug 33 having 15 a disc 36, which is also tapered as indicated. Secured to the valve disc 36 is a pair of spaced collars 34 between which is a reduced portion 35. Secured to the lower collar 34 is a reduced portion 44 acting as a guide for the valve disc, and 20 slidably mounted in the adjacent part of the wall 23.

The cap 24 has a depending member 29 to which is pivoted a lever 39 by means of a pin 42. The lever 39 is provided with a pair of forks 40, 25 which slidably receive the pin 41 which passes through the spindle 18. The lever 39 is provided with a pair of inwardly projecting extensions or ribs 43 engaging between the collars 34. The ends of the ribs 43 which engage the upper collar 34 in the position shown in Fig. 2 are rounded while the sides of the ribs 43 which engage the lower collar 34 to open the valve are flat.

It will be noted that the valve disc 26 is not threaded into the flange 25, and is simply removable therefrom by unscrewing first the plug 28 and then the threaded collar 27. The valve seat 26 may be replaced by a valve seat of the same size when worn, or it may be replaced by a valve seat of a different size to accommodate the trap 40 for use for different pressures.

Referring now to Fig. 5a, the valve seat 26a is shown to illustrate the effect of a valve seat having a smaller orifice 38a with respect to the same valve plug 33. It will be noted that the 45 tapered mouth 37a is necessarily extended but has the same angle of taper and remains in the same position relative to the operating mechanism for the valve plug 33 as the seat 26, and will seat the same plug. The valve seat 26a is the same size and shape as the valve seat 26 in all other respects. Thus no matter what size orifice 38 is used, the 50 same valve plug 33 will close the valve without requiring any adjustment of the operating mechanism.

By using a valve seat 26 having the proper size orifice 38 with the particular steam pressure used a force of substantially the same value is obtained with any steam pressure for holding the valve plug 33 on its seat and hence a constant 55 operating force will remove the valve plug 33 from its seat with all steam pressures used.

In operation, the water draining into the trap through the inlet opening 13 is prevented from being discharged directly into the bucket 17 by the branch openings 14. This water passes down the interior wall of the casing 10, filling up the casing, and exerting a buoyant effect on the float 17, assisting the steam pressure in holding the 60 valve plug 33 firmly seated against the seat. As the water rises in the casing to the top of the float 17, it overflows into the float. When the water reaches a predetermined level indicated for instance by the line A, the float rapidly sinks, 65 pulling down the lever 39 and causing it to ex-

ert a considerable blow on the lower collar 34, suddenly and positively opening the valve plug 33.

When the bucket once begins to fall, the water in the casing 10 and the water coming in through the branch openings 14 flow into the bucket, increasing the rapidity of its fall, thereby assisting in applying a considerable force to the valve plug to open the valve. Thus not only is considerable mechanical advantage by the lever 39 obtained but the force of the impact is also obtained, to open the valve quickly and 85 positively.

As soon as the valve is opened, steam pressure forces the water up through the tube 22 into the auxiliary chamber 101, and through the valve orifice 38, and passages 30, 31 and 15. The water continues to discharge until the water level in the float reaches a predetermined position, as for instance indicated by the line B. This causes the buoyant effect of the water in the casing 10 to overcome the weight of bucket assembly, and the bucket begins to rise with considerable velocity. Due to the lost motion connection the valve plug 33 does not begin to close until the ribs 43 engage the upper collar 34. 90 Due to the velocity of the bucket float 17, the studs 43 engage the upper collar 34 with considerable force, positively closing the valve plug 33. As soon as the valve plug 33 is closed, the pressure inside the trap assists in holding it closed. This condition obtains until the casing fills up with water sufficiently high to overflow into the bucket float 17, the cycle above described then being repeated.

Thus a trap for venting water from pressure mains has been described, which is simple in construction and effective in operation. The arrangement is such that considerable force is applied to the valve disc for both opening and closing, thereby assuring positive and quick opening and closing of the valve effectively preventing wire drawing. Furthermore, provision is made for easily renewing the valve seat when worn without further adjustments being necessary. In addition, the trap may be used with a wide range of steam pressures by using valve seats having different sized orifices, insuring the force necessary for opening and closing the valve being substantially the same for all steam pressures used. It will be understood that to open the valve, the steam pressure must be overcome and that the force exerted by the steam pressure is proportional to the product of the steam pressure and the area of the orifice in the valve seat. Thus for large steam pressures a smaller orifice is used. At the same time the orifice will be made of sufficient size so that all of the water to be vented will be expelled within an allowable time limit.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In a trap, a hollow casing having an inlet in its side wall, an open top bucket float in said casing, a spindle secured to the bottom of said float, a removable head for said casing, said head having a depending chamber with an opening in its top wall, a guide tube depending from the bottom wall of said chamber into said float, a removable cap closing the top opening of said 145

- chamber, said cap having a depending opening, a removable valve seat seated in said opening and having a conical mouth, a valve member having a conical plug engageable with said mouth and a collar spaced from said plug and a shank guided in the wall of said chamber, a fulcrum on said cap, said valve member being located between said depending member and spindle, and a lever pivoted to said fulcrum and to the top 5 of said spindle and having a bearing part located between said valve plug and collar, said valve plug and collar being spaced considerably greater than the size of said bearing part, whereby said float will gain substantial velocity and said bearing part will strike said collar a substantial blow to open the valve. 80
2. In a steam trap, a hollow casing having an inlet in its side wall, an open top bucket float in said casing, a spindle having a shoulder and a stem passing through the bottom of said float, a weight nut threaded on said stem to hold the wall of said float between said nut and shoulder, a removable head for said casing, said head having a depending chamber with an opening in 20 its top wall, a guide tube depending from the bottom wall of said chamber into said float, guide members on said spindle engaging said tube, a removable cap closing the top opening of said chamber, said cap having a depending shouldered 25 opening, a removable valve seat having a flange seated against said shoulder and a conical mouth, a valve member having a conical plug engageable with said mouth and a collar spaced from said plug and a shank guided in the wall of said 30 chamber, a depending fulcrum on said cap, said valve member being located between said depending member and spindle, and a lever pivoted to 35
- said fulcrum and having a forked end engaging a pin on the end of said spindle and having a bearing part located between said valve plug and collar, said valve plug and collar being spaced considerably greater than the size of said bearing part, whereby said float will gain substantial velocity and said bearing part will strike said collar a substantial blow to open the valve, said cap, top and casing have aligned passages leading from said cap opening, said casing having a threaded outlet connecting with said passages. 85
3. In a trap, a hollow casing having an inlet, an open top bucket float in said casing, a spindle secured to the bottom of said float, an auxiliary chamber at the top of said casing and having an opening in its top wall, a guide tube depending from the bottom wall of said chamber into said float, a removable valve seat at said opening and having a conical mouth, a valve member having a conical plug engageable with said mouth, means for guiding said valve member in said auxiliary chamber, a fulcrum in said chamber, said valve member being located between said depending tube and fulcrum, and a lever pivoted to said fulcrum and to the top of said spindle and having a lost motion connection with said valve member, a removable closure in said casing to give access to remove said valve seat, and additional and separate valve seats having different size orifices and having conical mouths with the same taper as said plug and first mouth, whereby different size seats may be used separately with different pressures and the range of movement of said plug is always the same. 90 95 100 105 110
